WOMAN'S CONFINING GARMENT

Harry M. Dolan, Manhasset, N. Y.

Application June 21, 1951, Serial No. 232,803

6 Claims. (Cl. 2-34)

1

The present invention relates to a woman's garment and more particularly to a woman's woven, seamless, preformed, confining garment. It is the primary object of the present invention to provide a woven, body encircling, confining garment which is preshaped during the weaving process and which has no seams therein. The absence of seams which cause unsightly bulges and marks which are apparent through the wearer's outer garments, has always been a desirable feature of a woman's confining garment, such as a girdle or corset. This is especially true of the light-weight confining garments that may be worn under sheer or semi-sheer formal dresses or ordinary summer dresses. The seams not only mar the smooth appearance of the wearer, but also have a tendency to mark and irritate the skin of the wearer. It can be seen, therefore, that a garment without seams is a very desirable one and it is for this reason that it is an object of the present invention to provide such a garment.

Heretofore, preformed, seamless, women's confining garments have been made of a knitted fabric. It is an object of the present invention to provide such a garment constituted of a woven fabric. A woven fabric is much lighter than the knitted fabric and supplies much more control. Moreover a woven fabric is thinner and smoother than a knitted fabric, both of which are properties desirable in a woman's confining undergarment. Knitted fabrics have a tendency to be rough and to irritate the wearer's skin. Moreover, woven fabrics have a greater appeal for the eye and can be made much more beautiful than knitted fabrics. This last mentioned feature is important in connection with such confining garments as girdles or corsets but is much more important in connection with confining garments designed to be worn as an outer garment such as a bathing suit.

It is also a primary object of the present invention to provide such a woven garment in which the degree of control exercised by the garment on the body of the wearer is properly regulated throughout the garment. A garment embodying the present invention will provide a strong confining force in the region of the abdomen, hip, and buttocks of the wearer but will not unnecessarily bind or overly confine the wearer in the region of her waist. The garment will, therefore, properly control the wearer with perfect comfort. This distribution of confining force or modulus of elasticity also reduces the tendency of the garment to climb up when it is worn.

2

It is also an object of the present invention to provide a garment in which there are no slide fasteners or any other form of opening and closing means that must be actuated during the donning or the removal of the garment. This is not only an added convenience to the wearer in the donning and removal of the garment but also eliminates another source of unsightly bulges that are apt to show through the wearer's outer garments.

It is a further object of the present invention to provide a garment that is woven to a permanent shape having pre-determined dimensions. The garment is thus woven to fit the wearer and no sewing or shaping operation is necessary to cause the garment to assume the proper shape. This shape is permanent and the garment may be repeatedly laundered without any change in shape being caused thereby.

20 These and other objects and advantages of the present invention will be more readily apparent from the following description and drawing of one specific embodiment of the invention, in which:

25 Fig. 1 is a front view of a girdle embodying the present invention;

Fig. 2 is a view similar to Fig. 1 showing the ranges and location of the various degrees of confining force exerted by the girdle; and

30 Fig. 3 is a front view of a modification of the invention.

Unlike the conventional woven garment, the garment in Fig. 1 is constituted of a single section of tubularly woven fabric. The only inclusion of sewing is in the formation of the upper hem 10 and lower hem 11 which are formed by stitching lines 12 and 13 respectively, and the securing of the conventional stocking supporters 14 thereto.

40 The garment is woven on a fly shot loom in the shape indicated in Fig. 1. In the preferred form, the weave is a taffeta or plain weave, but a satin, twill or any combination of these weaves may be used. The warp or binding threads run vertically in the garment and the weft or filling threads run horizontally in the garment.

In the preferred embodiment a rayon warp thread and a cotton covered rubber weft thread is employed. Thus, in the embodiment illustrated, the warp is constituted of substantially non-elastic yarns while the weft is constituted of a highly elastic rubber yarn covered or uncovered thread. However, this is not absolutely necessary and any type of warp yarn may be employed, such as animal, vegetable, synthetic

fibres, however, the actual elasticity and confining effect of the garment will, of course, vary with the type of weft or filling elastic yarn employed.

The shaping of the garment and the confining force exerted by the garment is determined by the weaving process and is dependent on the number of warp and weft threads per unit area in various portions of the garment. Therefore, while the same thread is used throughout the garment, the number of warp and weft threads per unit area is not constant, nor is the initial tension set in the weft threads constant throughout.

In the zone at the top of the garment, indicated by the brackets A, there is a substantially constant number of warp and weft threads per unit area. In the zone indicated by the brackets B the number of warp threads per unit area gradually decreases, and the number of weft threads per unit area gradually increases, until the zone indicated by the bracket C is reached. Throughout the zone C, the number of warp and weft threads per unit area is substantially constant, however, due to the changes accomplished gradually in the transition zone C there are more weft threads per unit area in zone C than in zone A and less warp threads per unit area in zone C than in zone A.

Not only are the number of threads per unit area different in each of zones A and C and gradually changing in zone B, but the pre-stretch of the weft or filling threads is also different in the various zones. Since the forces exerted by an elastic member varies directly with the distance it has been elongated, a greater confining force will be exerted by that portion of the garment in which the weft or filling threads have been bound into the woven fabric with the greater amount of extension therein. In zone A the filling or weft threads are under less tension than the weft or filling threads of the zone C, and therefore will react on the body of the wearer with less of a confining force. The tension in the weft or filling threads in zone B increases gradually from the border of zones A and B to the border of zones B and C. It can therefore be seen that the greatest confining force will be exerted by zone C of the garment where it is most desired.

It has been found that in the preferred form the relationship between the modulus of elasticity or confining force exerted by the several zones of the garment should be about two to one. In other words, if a force is applied to stretch zone A, and will stretch it a unit distance, the same force applied to stretch zone C will stretch it only one half a unit distance.

The garment of my construction will thus yield the utmost comfort at the waist portion because of minimum modulus of elasticity at such portion, but has a high degree of control around the hip portion where such control is most needed.

Fig. 3 illustrates a modification having a substantially inelastic panel 15 inserted in the front of the garment. The rest of the garment is constituted of a single section of woven fabric 16 hav-

ing the varying modulus as in the modification illustrated in Figs. 1 and 2 with the greater confining force being exerted by the lower portion of the garment corresponding to the zone C and the warp and weft ratio changing as described herefore.

It is accepted in the art that an inelastic panel insert has a tendency to increase the flattening effect of that portion of the garment and it is for this reason that the front, central, inelastic panel 15 is inserted in the modification illustrated in Fig. 3.

I claim:

- 15 1. A preformed confining garment comprising a segment of a woven tube of varying diameter having relatively inelastic warp threads and relatively elastic weft threads, the incidence of the latter progressively and gradually increasing with the diameter of the tube.
- 20 2. A preformed confining garment comprising a segment of a woven tube of varying diameter, the segment increasing in diameter from top to bottom, and having elastic weft threads the incidence of which progressively and gradually increases with said diameter.
- 25 3. A preformed confining garment comprising a segment of a seamless tubular woven fabric the diameter of which increases progressively and gradually from one end to the other thereof and having elastic filling threads the number of which increases progressively and gradually with said diameter.
- 30 4. A girdle comprising a seamless tubular woven fabric having rayon warp threads and elastic weft threads, the diameter of said garment and the number of weft threads progressively and gradually increasing from one end to the other thereof.
- 35 5. A girdle comprising a seamless tubular woven fabric having elastic weft threads, the diameter of said garment and the number of weft threads progressively and gradually increasing from one end to the other thereof.
- 40 6. A preformed confining garment comprising a segment of a seamless tubular woven fabric of varying diameter and having elastic weft threads the incidence of which and the fabric modulus of which increases progressively and gradually with said diameter.

HARRY M. DOLAN.
